COLLECTING FOLDER FOR FILING
DIAPHRAGM DISKSAlbert Becker, Villingen, Schwarzwald, Germany;
vested in the Alien Property CustodianApplication October 25, 1940, Serial No. 362,830
In Germany November 7, 1939

8 Claims. (Cl. 129—20)

This invention relates to a collecting folder for filing diaphragm disks.

For supervising the operation of motor vehicles apparatuses are commonly used by means of which the manner of operation, more especially the respective speed attained, is recorded on a diaphragm disk, mostly of circular shape. After the period of control comprising for instance one working day has expired, the recorded disk is removed from the apparatus and replaced by a new one. By way of the disk recordings accumulated during a larger period like a month or so, an accurate judgment can be obtained regarding the manner of operation of the respective driver.

The present invention has for its object to provide a collecting folder in which the individual disks successively recorded can be filed easily so as to permit clear suspension.

Another object of the invention is to provide a collecting folder of the type referred to which is of very small thickness even when filled with the disks.

With these and further objects in view, as may become apparent from the within disclosures, the invention consists not only in the structures herein pointed out and illustrated by the drawing, but includes further structures coming within the scope of what hereinafter may be claimed.

The character of the invention, however, may be best understood by reference to certain of its structural forms, as illustrated by the accompanying drawing in which:

Fig. 1 is an elevation of a collecting folder having the invention applied thereto, with the front layers partly broken away.

Fig. 2 is a rear view of the collecting folder, also partly broken away.

Fig. 3 shows a central longitudinal section through a part of the collecting folder, or of the individual folder pockets, on a considerably enlarged scale.

Fig. 4 is a central longitudinal section through another form of the invention.

Similar characters of reference denote similar parts in the different views.

As here shown, certain slots are arranged one below the other in the cover of the collecting folder for receiving the disks and behind each slot on the inside of the folder cover there is a separate receiving pocket for each disk. Said receiving pockets for the diaphragm disks are suitably made of thin paper or so-called tissue paper, so that the collecting folder filled with

disks may become very thin and occupy little space.

Referring now to the drawing in greater detail, it will be noted that a folder cover 1 consisting of strong paper, card board or similar material is provided with a certain number of slots 2 arranged one below the other, corresponding to the number of disks D which are intended to be kept in the folder; the length of each slot should suitably be chosen somewhat larger than the diameter of the circular disks D.

On the inside (Fig. 2) of the folder cover 1 certain leaves or sheets 3, 3', 3'' and so forth, consisting of thin paper, for example tissue paper, have been provided and arranged shingle-like against each other. The upper edge of the uppermost sheet 3 is glued to the backside of the folder just above the first slot 2. The sheet 3' below is glued below the first slot 2 and above the second slot 2, that is to say, it is glued to the ridge remaining between the two slots. In the same manner the subsequent paper leaves 3'' and so forth are fastened to the ridges above their respective slots 2. Furthermore, all leaves 3, 3' and so forth, which are arranged shingle-like below each other, as mentioned above, are fastened on their sides to the back wall of the folder cover 1 by means of gummed strips 4. Another gummed tape 5 runs along the center between the lateral strips 4, starting from the lower edge of the uppermost paper leaf 3 past all the subsequent leaves 3', 3'' and so forth, being fastened by its lower edge to the inside of the folder cover 1. A gummed strip 6 serves to protect the upper edge of the uppermost paper sheet 3.

In this manner a number of receiving pockets for the diaphragm disks D have been created, corresponding to the number of receiving slots 2, as may be seen more particularly from the cross section according to Fig. 3. The diaphragm disks are introduced into these pockets from above by the slots 2. The bottom of the pockets is formed essentially by the central gummed strip 5 which in cooperation with the individual paper leaves 3, 3' and so forth prevents the disks D from slipping out of the bottom of their pockets.

The inside of the folder cover 1 supporting the receiving pockets is finally covered by a back sheet 7 so that the receiving pockets which are suitably made of sensitive tissue paper are protected.

It may be advisable to print on the outside 55 of the folding cover 1 various desirable refer-

ences and data as to the date, the vehicle under supervision, the driver, the mileage covered and so forth, as exemplified in Fig. 1. Owing to the echelon arrangement of the disks in their pockets, supervision is greatly facilitated. By way of alternative the back sheet 7 can be replaced by another folder cover 1 which is likewise provided with receiving pockets corresponding to the cover 1. In this case both parts 1 of the folder lie on top of each other with the receiving pockets arranged at their inner sides, being glued to each other at their edges. In this way the diaphragm disks can be introduced into the pockets from both sides of the folder and it is therefore possible to accommodate a relatively large number of disks in each single folder in clear view of the user. An arrangement of this type is illustrated in Fig. 4, in a longitudinal section.

The apparatus of the present invention has been described in detail with reference to specific embodiments. It is to be understood, however, that the invention is not limited by such specific reference but is broader in scope and capable of other embodiments than those specifically described and illustrated in the drawings.

I claim:

1. A folder for filing disks, comprising a cover formed with a series of parallel slots, a pocket at the back of the cover behind each slot, for reception of the disks, said pockets being formed of paper sheets being offset below each other and secured at their upper edges to the edges of the slots and at their side edges to the back-side of the cover, and at least one strip interconnecting the lower edges of the paper sheets overlapping each other shingle fashion.

2. A holder for filing diaphragm disks comprising a cover provided with a series of closely adjacent substantially horizontal slots leaving a narrow strip of cover paper between each pair of adjacent slots; thin sheets secured at their upper margins only to the inner faces of said narrow strips respectively, each sheet being secured to only one strip; each margin lying in the plane of the sheet, only one sheet being secured to a strip; said sheets being unsecured except at their margins, adjacent sheets forming a disk receiving pocket therebetween, each intermediate sheet forming a partition wall between two pockets, each strip and the attached sheet cooperating to form the upper part of the wall; and means for securing together the lower marginal portions of said sheets.

3. In a holder as in claim 2, each slot and strip next below it being frontwardly offset from the strip above, whereby the slot is outwardly positioned to facilitate the insertion of the disk.

4. A holder for filing diaphragm disks comprising a cover provided with a series of closely adjacent substantially horizontal slots leaving narrow strips of cover paper between the slots; thin sheets glued at their upper margins

only to the inner faces of said narrow strips respectively, each sheet being secured to only one strip, each strip carrying only one sheet, each of said margins being unfolded and lying in the plane of the sheet; said sheets being substantially of the same width from top to bottom and extending downwardly in planes substantially parallel to and back of said cover to a distance slightly less than the diameter of said disks; the lower margins of the sheets being stepped in shingle-like relation, said sheets being unsecured except at their margins.

5. A holder as in claim 4 comprising side strips of paper-like material secured to said sheets collectively at their respective side margins and to the rear face of the cover for holding the sheets in place, and to hold the ends against the cover.

6. A holder as in claim 4 comprising an intermediate strip secured to the rear face of the lower marginal portion of each of said sheets for preventing the disk from completely passing through said slots and having its lower end secured to said cover for holding the intermediate parts of the sheets close to the cover.

7. In combination, a cover of strong paper provided with a series of closely adjacent substantially horizontal slots leaving a narrow strip of cover paper between each pair of adjacent slots; an upper sheet of thin material having the upper inner marginal portion thereof mounted on the rear face of the upper marginal portion of the upper slot, with its side edges even with the ends respectively of the slots; similar thin sheets secured at their upper margins only to the inner faces of said narrow strips respectively, each sheet being secured to only one strip, each of said margins being unfolded and lying in the plane of the sheet, only one sheet being secured to a strip; said sheets extending downwardly; the lower margins of the sheets being stepped in single-like relation; said sheets being unsecured except at their margins, each intermediate sheet forming a wall of two pockets; a round disk in each pocket; side strips of paper-like material secured to said sheets collectively at their respective side margins and to the rear face of the cover for holding the ends of the sheets in place on the cover; and an intermediate strip secured to the rear face of the lower marginal portion of each of said sheets and engaging the lower edge of the disks and holding the disks projected from the slots, the lower end of the intermediate strip being secured to said cover for holding the intermediate parts of the sheets close to the cover.

8. A holder as in claim 7 comprising a gummed strip secured on the upper margin of the upper sheet and the adjacent portion of the cover above it, to protect the upper edge of the upper sheet; the upper edges of each of the other sheets being protected by sheets above it.

ALBERT BECKER.
